UNITED STATES PATENT OFFICE.

CHARLES E. BROOKS, OF MONTREAL, CANADA, AND CARL A. BRANDT, OF GREAT NECK, NEW YORK; SAID BRANDT ASSIGNOR TO THE SUPERHEATER COMPANY, OF NEW YORK, N. Y.

STEAM LOCOMOTIVE.

Application filed April 13, 1923. Serial No. 631,944.

Our invention relates to locomotives, and more particularly to throttles for controlling the admission of steam to the valve chests. It has particular application to locomotives using superheated steam, but its use is not limited in this respect.

The invention is illustrated in the accompanying drawings, where Fig. 1 is a side view of a locomotive equipped with our invention; and Fig. 2 is a front view of the same locomotive, the right half being partly in section on a plane through the steam-pipe, the steam pipe being shown in full and its covering from the smoke-box to the steam chest being omitted. In both figures some of the parts, having no bearing on the invention, have been omitted.

The locomotive in connection with which we show our invention is of a usual type. 20 Steam generated in the boiler is carried by the dry-pipe 1 to the superheater header 2, leaves this header to flow through the superheater elements 3, lying in the flues 4, and returns in a superheated condition to the header. All this is in accordance with ordinary and well-known practice.

In locomotives as arranged hitherto, it has been the common practice to place the throttle controlling the steam flow in the steam dome where the steam generated in the boiler collects and enters the dry pipe. 30 We are aware that it has been proposed heretofore to place the throttle or throttles between the superheater header and the steam-chests; and the advantages of this 35 location for the throttle are well understood. None of the arrangements proposed, however, have been practical or gone into use; and it is the object of this invention to provide an improved arrangement of this kind 40 which is practical and eliminates the objections which obtained in others.

To this end we employ two throttles, placing one adjacent to each steam chest. One 45 of these appears at 5, Fig. 2, while the other lies in the part of the casing shown at 5^a in Fig. 1. Steam is supplied to valve 5 by steam pipe 6 leading from the header 2. It will be understood that a corresponding pipe (not shown) carries steam from the header 50 to the throttle on the other side, in casing 5^a. The throttles may be of any type desired, but are preferably balanced, double-seated.

As their construction plays no part in the invention it is unnecessary to illustrate it. 55

The two throttles are operated in unison from the cab by the lever 7. The rod 8 extends forward from this lever and is connected at its forward end to the arm 9. This arm is secured to the rod 10 and rotates 60 it in the trunnions 11-11. A ring 12 is secured to the rod 10 adjacent to the outside of the farther trunnion to keep the rod in place. Also secured to the rod 10 are two arms 13, 13 from which extend downward 65 the two rods 14, 14. The lower ends of these rods are pivotally connected to the levers 15-15. Each lever 15, as will be more clearly seen in Fig. 1, has its farther end pivoted at 16 in the fixed bracket 17, and has 70 an operative connection with throttle stem 18 through the links 19 and yoke 20. For the sake of clearness the levers 15 are shown in section in Fig. 2, the brackets 17 also being omitted, so that the construction of the 75 yokes 20 might be visible.

By the arrangement described, the desirable object is obtained of having the throttles each in immediate proximity to its valve chest, which we consider a very important feature of the invention. By having them so placed the volume of steam between the throttles and the cylinders, after the throttles are closed, is reduced to a minimum; and on the other hand, when the 80 throttle is opened, the steam at once acts on the pistons without the necessity of first filling up any large spaces. The action of the locomotive is thus materially improved.

The reduction of the volume of steam between the throttle and the engine has the further great advantage that it minimizes the slipping of the drivers. When slipping occurs, the engineer promptly shuts off the steam supply by closing the throttle, but 85 the steam trapped between the throttle and engine will continue to actuate the engine and prolong the slipping of the drivers until its pressure has fallen to a point where it is insufficient to drive the piston. By 90 cutting down to a minimum the volume trapped, the promptness with which the slipping is stopped is correspondingly increased.

What we claim is:

1. In a locomotive, the combination of a 100 pair of flue sheets, flues connecting them, a

- smoke-box into which the flues open at one end, a bi-chambered superheater header extending across the upper portion of the smoke-box adjacent to the flue sheet, tubular
5 superheater elements extending into the flues and having their ends respectively secured to the two header chambers, a dry-pipe connecting one of the chambers to the boiler steam space, a pair of main distribution
10 valve chests, a throttle adjacent to each outside of the smoke-box, and arranged and adapted normally to control and regulate the steam supply to it, a steam pipe from the second header chamber to each throttle,
15 and mechanism to actuate said throttles from the cab.
2. In a locomotive the combination of a boiler provided with flues, a superheater comprising elements lying in the flues and
20 a header in the smoke-box to which the elements are secured, a dry-pipe to carry steam from the boiler to the header, a pair of main distribution valve chests, a throttle adjacent to each valve chest and arranged and adapt-
25 ed normally to control and regulate the

steam supply to it, a pipe from the header to each of the throttles, and mechanism to actuate said throttles simultaneously from the cab.

3. In a locomotive equipped with a super- 30 heater the combination of the usual two main distribution valve chests, a throttle adjacent to each of them and arranged and adapted normally to control and regulate the steam supply to it, two pipes each connecting the superheater to one of the throttles, and mechanism to operate said throttles simultaneously from the cab.

4. In a locomotive, the combination of the usual two main distribution valve chests, a 40 throttle adjacent to each of them and arranged and adapted normally to control and regulate the steam supply to it, two pipes supplying steam from the boiler steam space to the two throttles, and mechanism to operate 45 said throttles simultaneously from the cab.

C. E. BROOKS.
